[57] CLAIM

The ornamental design for a granular coffee dispenser attachment for a beverage maker or similar article, as shown and described.

DESCRIPTION

FIG. 1 is a front perspective view of a granular coffee dispenser attachment for a beverage maker embodying my new design;

FIG. 2 is a top plan view thereof;

FIG. 3 is a front elevational view thereof;

FIG. 4 is a rear elevational view thereof;

FIG. 5 is a right side elevational view thereof, the left side being substantially a mirror image thereof;

FIG. 6 is a bottom plan view thereof.

FIG. 1.

FIG. 2.

FIG. 3.

FIG. 4.

FIG. 5.

FIG. 6.
